UNITED STATES PATENT OFFICE.

GEORGE WASHINGTON WALKER AND ERASTUS HARKNESS HARRY, OF GIBSON CITY,
ILLINOIS; SAID HARRY ASSIGNOR TO SAID WALKER.

SCAFFOLD.

1,213,043.

Specification of Letters Patent. Patented Jan. 16, 1917.

Application filed March 16, 1916. Serial No. 84,584.

To all whom it may concern:

Be it known that we, GEORGE W. WALKER and ERASTUS H. HARRY, citizens of the United States, and residents of Gibson City, 5 in the county of Ford and State of Illinois, have invented an Improvement in Scaffolds, of which the following is a specification.

This invention is an improvement in adjustable scaffolding and has particular reference to an apparatus employed in building circular structures wherein a scaffold 10 can be used in the interior thereof.

An object of the invention is to facilitate the erection of silos and similar structures by providing a scaffold which may be readily assembled and which includes a working platform vertically adjustable in a novel manner and effectively supported in its adjusted positions.

20 In carrying out this object, the invention comprises a central standard having relatively adjustable sleeve elements supported thereon, one of said elements having extending therefrom a plurality of platform supporting arms connected to the other sleeve element by suitable bracing members. 25 A hoisting device is associated with the sleeve elements in such a manner as to adjust the same relative to each other whereby 30 the platform may be raised and lowered to any desired position as the building of the structure progresses.

Another object is the provision of a novel hoisting for supplying material to the workmen on the platform, said device consisting of a rotatable crane connected to one of the sleeve elements and maintained in its adjusted positions by a novel support.

A further object is the provision of 40 scaffolding of this character which is simple in construction, easy to manufacture and effective in carrying out the purpose for which it is designed.

The inventive idea involved is capable of 45 receiving a variety of mechanical expressions, one of which, for the purpose of illustrating the invention, is shown in the accompanying drawings, in which—

Figure 1 is a side elevation of the apparatus constructed in accordance with the invention and showing the same employed in connection with a concrete silo. Fig. 2 50 is a detail perspective of one of the bracing devices used in connection with the invention.

Fig. 3 is a section on the line 3—3 of 55 Fig. 1. Fig. 4 is an enlarged fragmentary vertical section of a portion of the apparatus. Fig. 5 is a top plan view of the upper sleeve element. Fig. 6 is a side elevation of the crane supporting device employed in connection with the invention.

There is illustrated what is now believed to be a preferred form of the invention, in which all of the parts are preferably made of steel and which comprises a base 10 65 adapted for engagement with the ground and preferably positioned centrally of the concrete structure 11. Mounted in the base is a standard 12 including a number of sections all of which are provided with small 70 openings 13. These sections are of hollow construction and each superposed section is provided with a reduced extension 14 which fits into the upper end of the section below and is secured in position by means of locking pins 15 which engage registering openings 13.

A number of bracing devices are employed for supporting the standard 12 in position and each of these devices includes 80 a collar 16 surrounding the standard and supported in position by means of a locking pin 17 engaging in one of the openings 13 in the standard. A plurality of horizontally arranged bearings 18 extend radially 85 from the collar 16 and each bearing has mounted thereon a bracing arm 18' preferably made in sections the outer one 19 of which is slidably mounted within the inner section whereby said arm may be adjusted 90 to any length desired so as to engage the inner wall of the structure 11.

The platform structure includes upper and lower sleeve members 20 and 21, the latter member being provided in its periphery with a number of radially arranged openings 22 for receiving the inner ends of the hollow platform supporting arms or members 23 preferably made of flexible steel tubing. These arms 23 are also made 100 in sections whereby the same may be adjusted to any length desired. Each arm 23 is provided with an eye 24 through which is passed one end of a flexible member 25, such as a chain, the other end of which is 105 connected to an annular flange 26 formed upon the upper sleeve member 20. The other end of the chain 25 is preferably

provided with a hook 27 which is adapted to engage any one of the links of the chain after the same has been drawn taut and in position to support the arm 23 to which it is connected. The sleeve members 20 and 21 are retained in adjusted positions by means of locking pins 28 extending through openings 13 in the standard beneath said members. A plurality of platform boards 29 are laid upon the supporting arms 23 adjacent the outer extremities thereof, said boards being arranged as shown in Fig. 3 with their ends overlapping.

A platform adjusting device is employed for raising and lowering the platform and comprises oppositely disposed operating levers 30 pivoted at their inner ends at 31 to the upper sleeve member 20 and normally extending in an upward direction, as shown in Fig. 1 when the outer extremities of the arms 23 engage the wall of the structure. To each of the levers 30 is secured, adjacent its pivoted end, one end of a connecting link 32 the other end of which is pivoted at 33 to the sleeve 21. It will be seen from this description that when the free ends of the levers 30 are lowered the upper sleeve member 20 will be raised through the medium of the connecting links 32 whereupon the outer ends of the arms 23 will be elevated and detached from engagement with the structure wall. When in this position, the lowermost locking pin 28 under the sleeve 20 is withdrawn and again inserted into an opening 13 below said sleeve. Then by raising the free ends of the levers 30 the lower sleeve member 21 will be raised until the desired position is reached and the arms 23 are substantially horizontal whereupon a pin 28 may be inserted beneath said sleeve in order to support it in its adjusted position. The outer ends of the arms 23 will again be adjusted into contact with the structure wall and any movement of the scaffold will be prevented.

A material hoisting apparatus is employed and consists of a rotatable ring member 34 fitted into an annular groove 35 formed in the periphery of the sleeve member 20 adjacent the upper end thereof. The ring member 34 is provided with a number of bearings 36 in either of which is mounted the lower end of a vertical arm 37 provided at its upper end with a coupling 38 from which extends a sectional crane arm 39 the outer end of which has secured thereto a hook 40 for supporting the pulley 41. A support is provided for maintaining the crane arm 39 in an adjusted position and consists of a pair of pivoted members 42 having notches 43 in the upper ends thereof for receiving said arm 39. One of the members 42 has secured thereto adjacent its lower end one end of a brace 44 the other end of which is provided with a longitudi-

nal slot 45 for receiving a fastening screw 46 which engages the other arm 42 and retains said arms in their adjusted positions. This support is preferably mounted upon the platform boards 29 as shown.

What is claimed is:

1. A scaffolding apparatus comprising a sectional standard having a plurality of openings therein, upper and lower sleeve members mounted on said standard and relatively adjustable to each other, means engaging the openings in said standard for supporting said sleeve members in adjusted positions, a plurality of sectional and resilient platform board supporting arms extending radially from said lower sleeve member and engaging the wall of a structure, flexible brace connections between said arms and the upper sleeve member, a device for adjusting said upper and lower sleeve members relative to each other, said device including oppositely disposed levers pivoted to said upper sleeve member, and connections between said levers and the lower sleeve member whereby the upper sleeve member is raised when the levers are lowered and the lower sleeve member raised when the levers are raised.

2. A scaffolding apparatus comprising a standard, upper and lower platform supporting sleeve members mounted upon said standard and adjustable relative to each other, resilient supporting arms extending from one of said members and having their outer ends in contact with the wall of a structure when said arms are in horizontal position, and means for alternately shifting said arms from horizontal to diagonal positions and adjusting said sleeve members whereby to raise the apparatus.

3. A scaffolding apparatus comprising a standard, upper and lower sleeve members mounted upon said standard and adjustable relative to each other, resilient platform supporting arms extending from one of said sleeve members and having their outer ends in contact with the wall of a structure when the arms are in substantially horizontal position, flexible connections between said upper sleeve member and said supporting arms and lever connections between said sleeve members adjustable in one direction for raising said upper sleeve member and exerting upward pull on said flexible connections to disengage the outer ends of said platform supporting arms and adjustable in the opposite direction to raise said lower sleeve member to again cause the outer extremities of said platform supporting arms to engage the wall of the structure.

4. A scaffolding apparatus comprising a standard, upper and lower sleeve members mounted thereon and adjustable relative to each other, resilient platform supporting arms extending from one of said sleeve mem-

bers and having their outer ends in contact with the wall of a structure when the arms are in a substantially horizontal position, and means for adjusting said sleeve members relative to each other whereby to raise the outer ends of said supporting arms out of contact with said structure wall, said

means being also operated to raise the sleeve member to which said supporting arms are connected after the outer ends of said arms have been raised whereby said ends are again caused to contact the structure wall.

GEORGE WASHINGTON WALKER.
